UNITED STATES PATENT OFFICE.

WALTER H. COTTON, OF CHICAGO, ILLINOIS, ASSIGNOR TO UNION DRAFT GEAR CO., A CORPORATION OF ILLINOIS.

DRAFT-GEAR.

1,243,389.

Specification of Letters Patent. Patented Oct. 16, 1917.

Application filed October 19, 1915. Serial No. 58,655.

To all whom it may concern:

Be it known that I, WALTER H. COTTON, a citizen of the United States, and resident of Chicago, county of Cook, and State of Illinois, have invented certain new and useful Improvements in Draft-Gears, of which the following is a specification, and which are illustrated in the accompanying drawings, forming a part thereof.

10 The invention relates to draft gears for railway cars, of the friction type. Its object is to secure, with high efficiency, compactness of form and improved adaptability to environment.

15 The invention consists in a structure such as hereinafter described, and which forms one of its embodiments, and as illustrated in the accompanying drawings, in which—

Figure 1 is a plan section of the gear as applied to the draft sills of a railway car, some parts being shown in plan,

Fig. 2 is a longitudinal central vertical section of the gear, some of the parts being shown in elevation,

25 Fig. 3 is a view similar to Fig. 1, the gear being under compression, and

Figs. 4, 5 and 6 are views of several of the elements of the gear.

In the drawings a pair of draft sills are represented at 10, 11, these sills being provided with draft lugs 12, 12 and buffing lugs 13, 13. There is also shown a butt end of a coupler 14 and a coupler extension or yoke 15 for inclosing the gear.

30 These various parts may be of any preferred form, with the exception of the yoke, which, as will hereinafter appear, is provided with an aperture in its rear or transverse end.

40 The friction elements of the gear are inclosed within a pair of box like followers 16, 17, adapted to fit within the yoke 15 and to engage respectively the draft lugs 12 and buffing lugs 13.

45 Within each of these followers or casings is inclosed a friction element comprising a group of members having engaging inclined faces. As shown, the members of each group, so far as relates to their external configuration are alike. Each friction element comprises a pair of triangular blocks 18, 19, adapted to fit within the side corners of a casing, their inner faces being inclined outwardly with reference to the center line of 50 draft from the bottom of the box like casting. A second pair of blocks 20, 21, shown

as having the form of an equilateral triangle are fitted, respectively, to the inner faces of the blocks 18, 19, and thus have one side face perpendicular to the center line of draft. A fifth block 22, shown as having the form of a truncated cone, is interposed between the blocks 20, 21. Located between the two friction elements there is a friction plate 23, perpendicular to the axis of the gear and preferably of the same area as the open ends of the box like followers. The members 20, 21, of each of the friction elements are seated against the plate 23 and are preferably interlocked therewith by means of a rib 24 formed on the plate contacting face of the block and adapted to enter and slide in the channel 25 in the plate.

The spring element for effecting the recoil of the gear is located back of the yoke 15 and is carried by a rod 26 which projects through a suitable aperture in the cross member 27 at the rear end of the yoke, and apertures in the follower 17, the center wedging member 28 of the rearward friction element, the plate 23 and the central wedging member 22 of the forward friction element, and at its forward end is provided with a head 29 housed within the recess in the member 22 and which prevents its withdrawal therefrom. For convenience in assembling this head is preferably T-shaped and the several apertures in the members 28, 23 and 22 are elongated to permit its entry. The rod having been inserted through the various members is given a quarter turn and then drawn back until the head enters lateral recesses extending from the aperture in the block 22 whereby the rod is prevented from turning. When in position of service, the inner end of the rod is entirely inclosed within the recess in the block 22. An abutting plate 30 for the spring element is mounted upon the rear end of the rod 26 and secured by any suitable means such as a nut 31 screwed upon the rod. The abutting plate 32 for the forward end of the spring element is sleeved upon the rod and is in sliding engagement therewith, and is provided with a tubular stem 33 which projects through the aperture in the rear end of the yoke 15 and the aperture in the follower 17, and abuts against the central wedging member 28 of the rearward friction element. Preferably the spring element is composed of a group of springs. As shown, this group of springs comprises a pair of

outer helical coils 34, 35, and a pair of inner coils 36, 37, the two sets being arranged in tandem and a plate 38 being interposed therebetween. This arrangement is proposed merely because it provides for the use of 5 springs of the present standard length and size in railroad service, though obviously the desired action may be secured by the use of a single spring coil and of ample size, in 10 place of the four coils shown.

When the gear is employed and in position of rest, the parts assume the relative position shown in Fig. 1, the followers 16, 17, bearing respectively against the draft 15 and buffing lugs, the plate 23 being midway between these lugs, the blocks 22 and 28 being in engagement with the plate and the blocks 20, 21, being thereby separated. The parts are held in this relation by the 20 spring element which in forcing the abutment plates 30, 32, apart by its expansion, has forced the blocks 22, 28, toward each other. The resulting outward movement of the blocks 20, 21, has caused the separation 25 of the followers by the wedging action of these blocks 18, 19.

Under buffing stresses the parts ultimately assume the relative position as shown in Fig. 3. The forward follower 16 being 30 moved inwardly, the blocks 18, 19, cause the relative approach of the blocks 20, 21, which in turn, cause the recession from the plate 23 of the blocks 22, 28, the movement of the block 22, however, being relative as to the 35 plate, the plate, in fact, being the movable member. The movement apart of the blocks 22, 28, causes the compression of the spring element, the abutment plate 32 being moved backwardly with the block 28. The over 40 compression of the spring element is prevented by the contact of the inner ends of the box like followers with the plate 28. Preferably these followers are provided with inwardly projecting lugs 39 for engagement 45 with the plate. As the gear is compressed friction is developed between the blocks 22 and 28 and the blocks 20, 21 with which each coöperates; between the several blocks 20 and 21, and the plate 23, and between the 50 blocks 18, 19 and the blocks 20, 21.

When the buffing pressure is reduced, the expansion of the spring element causes the movement apart of the abutment 30, 32 and thereby the relative approach of the blocks 55 22, 28. The blocks 20, 21 are thus wedged outwardly and coöperating with the blocks 18, 19, ultimately restore all of the elements to the position of Fig. 1.

Under the influence of stresses of draft 60 the relative movements of the various parts are the same, except that the rearward follower 17 is moved forwardly by the yoke 15.

While a preferred and operative construction is shown, the invention may be variously embodied, and I do not, therefore, desire to be limited to the particular form, disclosed.

I claim as my invention,—

1. In a draft gear, in combination, a pair of open faced casings alined on the line of draft, friction elements in each casing, each of such elements comprising inwardly wedging faces, triangular blocks bearing against such wedging faces and central wedge blocks, a yoke inclosing the casings and having an apertured cross member at its rearward end between the triangular blocks; a tension rod, attached to and extending backwardly from the forward central wedge block, a spring abutment at the rear end of said rod, a thrust rod engageable with the rear face of the rearward central wedge block, a spring abutment at the rear end of the last named rod, and spring means interposed between the two abutments, both of the named rods 8 extending through the aperture of the cross member of the yoke.

2. In a draft gear, in combination, a yoke having its rear end apertured, friction elements within the yoke, a spring back of the 90 yoke, and connection through the yoke aperture between the friction elements and the opposite ends of the spring.

3. In a draft gear, in combination, a yoke, two sets of friction elements inclosed within the yoke, a transverse plate interposed between and frictionally engaged by the friction elements, a spring exterior of the yoke and in line with the gear, such spring reacting on the two sets of friction elements. 95

4. In a draft gear, in combination, a pair of opposed followers, two sets of friction elements interposed between the followers, a transverse plate interposed between and frictionally engaged by the friction elements, a spring back of the rearward follower and located on the axis of the gear, abutments between which the spring reacts, and connection between each abutment and one of the sets of friction elements. 10

5. In a friction draft gear, the combination with front and rear followers having inclined friction faces, opposed central wedge-blocks having inclined friction faces, two pairs of wedge-blocks having friction faces 11 for engaging the friction faces of the followers and the central wedge-blocks, and a transverse plate interposed between the two pairs of wedge-blocks, of a single set of draft springs for opposing movement of the friction members under both draft and buffing stresses. 12

WALTER H. COTTON.
